MACHINE FOR SHAPING SHOE UPPERS
OR PARTS THEREOF

Joseph Fausse, Melrose Highlands, Mass., assignor to United Shoe Machinery Corporation, Paterson, N. J., a corporation of New Jersey

Application January 6, 1936, Serial No. 57,790

14 Claims. (Cl. 12—7)

This invention relates to machines for operating upon shoes or shoe parts and is exemplified herein with reference to the shaping of the toe portion of an assembled shoe upper or part 5 thereof into the form it is to have in the finished shoe.

As is well understood by those skilled in the manufacture of shoes of the stitchdown type, the upper may be so formed about the toe portion 10 of a last or form as to cause the marginal portions of the upper which extend beyond the edge of the last bottom to project outwardly from the last as a flange substantially parallel to the last bottom. Moreover, if the shoe is to 15 have an innersole, the marginal portions of the toe box and lining may be flanged inwardly under the margin of the innersole; but if there is no insole and one or more outsoles the lining and box are flanged outwardly with the upper. Such forming of the various upper parts into 20 conformity to the toe portion of the last and the flanging either outwardly or inwardly of the upper parts, especially with regard to the toe box, even though it has been rendered pliable to facilitate such an operation, presents difficulties which it is a general object of this 25 invention to overcome, it being understood that the invention contemplates shaping shoe uppers or parts thereof either on the last over which they are finally shaped or about another type of 30 form as a preforming operation preparatory to their being assembled and shaped about the last.

One object of the present invention, by which 35 is effected a substantial advance in the practice of shaping an upper part about a form and flanging its marginal portions outwardly from the form, is to effect control of the outwardly flanged marginal portions of the upper continuously throughout the shaping of the upper 40 part into conformity to the side and end surfaces of the form and the flanging of the marginal portions of the upper part outwardly from and continuously with the bottom of the form.

To this end, the illustrated machine includes, 45 as an important feature of the invention, the combination of a support having a surface adapted to be engaged by the form bottom and extending outwardly therefrom to an edge substantially parallel to the edge of the form bottom, a clamp plate having an edge complementary to that of this support, wipers mounted 50 for movement toward and away from the clamp plate, and means for moving the wipers successively to cause them to flange one section of

the marginal portion of the upper against the clamp plate and to flange the section of the marginal portion of the upper not engaged by the clamp plate against the support. Such flanging of the marginal portion of an upper 5 may be effected, as in the present instance for example, by mounting the wipers, in accordance with another feature of the invention, in overlapping relation with the clamp plate whereby the portions of the wipers which overlap the 10 clamp plate cooperate with that portion of the support for the form which extends beyond the bottom of the form. Accordingly, the outwardly flanged portion of the upper is gripped continuously throughout the flanging operation at 15 the end of which the outwardly flanged portion of the upper is completely gripped at its upper side by the wipers and at its lower side by the clamp plate and form support.

In accordance with another feature of the 20 invention, the above-mentioned wipers are spaced from the clamp plate normally in planes at an angle to each other to facilitate the placement of upper parts to be operated upon on the clamp plate; but the wipers are movable toward 25 the clamp plate into substantially the same plane, thereby to provide adequate gripping of the upper and to cause it to be pulled firmly against the form during the down wipe imparted to the upper part by the wipers in their 30 heightwise movement directed toward the form bottom.

However, if the upper part or parts are to be flanged inwardly under the form, the above-mentioned form support is dispensed with in 35 favor of another support which is arranged to engage the bottom of the form inwardly from its edge to obviate any interference with the wipers which are to be moved longitudinally and laterally of the form to wipe the upper part inwardly across the form bottom. Another object of the invention is to provide simple and effective means for operating the wipers to wipe the margin of the upper part inwardly across the bottom of the form after they have completed 40 their down wipe on the upper part to shape it about the end and side surfaces of the form.

To this end and in accordance with another 50 feature of the invention, the wipers are mounted, in the illustrated machine, for movement toward and away from each other laterally of the form on a carriage adapted to be moved successively heightwise and longitudinally of the form and means is provided for operating said wipers com- 55

prising a member mounted on the carriage for movement relative thereto, and other means for moving this member relatively to the carriage mounted and arranged to be actuated by movement of the carriage longitudinally of the form.

As herein illustrated, the above-mentioned member is constituted by a slide mounted freely to rotate and to move axially in the carriage, provision also having been made, in accordance with another feature of the invention for adjusting the wipers laterally of the form by means connecting the wipers and the slide constructed and arranged to swing the wipers toward or away from each other in response to rotative movement of the slide.

Invention is also to be recognized in the provision of means for effecting and controlling the movement of the carriage comprising a guideway having connected sections extending heightwise and longitudinally of the form, a follower received in said guideway, and treadle-operated means movable with a continuous stroke in a direction oblique to the sections of the guideway whereby the wipers which are mounted on the carriage are caused successively, by actuation of the treadle-operated means, to impart a down wipe to an upper part on the form and then are moved longitudinally of the form to wipe the upper part inwardly across its bottom.

These and other features of the invention will appear more fully when read in connection with the accompanying drawings and will be pointed out in the appended claims.

In the drawings,

Fig. 1 is a view in side elevation of an illustrative machine embodying the invention;

Fig. 2 is a front elevational view of the machine illustrated in Fig. 1;

Fig. 3 is a fragmentary sectional view, parts being omitted and broken away, taken along the line III—III in Fig. 1;

Fig. 4 is a plan view of the machine as viewed in a direction perpendicular to the plane of the section III—III certain parts being omitted;

Figs. 5, 6 and 7 are fragmentary sectional elevations, the sections being taken vertically through the center of the operating instrumentalities, illustrating successive stages in the shaping and inward flanging of a box toe and lining about the toe end of a form or last; and

Fig. 8 is a fragmentary vertical sectional view which illustrates the outward flanging of shoe upper parts after they have been shaped about the toe portion of the form or last.

The illustrated machine comprises a pedestal 10 in the upper end of which is mounted for vertical adjustment a column 12 carrying a frame 14 on which are mounted a horn 16 for supporting a form such as a last L over which shoe parts are to be shaped and also the shaping instrumentalities themselves, which will be described hereinafter. The horn 16, at its lower end, is mounted for heightwise adjustment in an arm 18 extending forwardly from the frame 14 and may be clamped in any desired position of adjustment by a set screw 20 threaded in the arm 18. The upper end of the horn 16 is bent and tapers rearwardly of the machine toward its tip 22 which is arranged to engage and support the toe portion of the last when the machine is used to flange the upper parts inwardly over the edge of its bottom as will be described later. Assisting the horn tip 22 in this function are a pair of studs 24 (Figs. 2 and 5) threaded into the horn 16 at each side thereof for heightwise adjust-

ment, thereby to provide, with the horn tip 22, a three-point support for adjustably positioning a last held thereagainst.

Taking the place of the above-mentioned last-supporting means when it is desired to flange shoe parts outwardly from the bottom of the last is a support 26 having a U-shaped surface 28 arranged to extend continuously with the bottom of the last and outwardly to an edge substantially parallel to the edge of the forepart portion of the last bottom. The support 26 is capable of being swung out of and into its operative position on a shaft 30 carried by the horn, the operative position of the support 26 being determined by lugs 32 which extend from the horn 16 and engage the lower side of the support 26. The illustrated machine will next be described with reference to its use in flanging shoe parts outwardly from a last bottom when the bottom of the last is supported primarily by the support 26.

In carrying out this operation the upper parts to be formed about the toe end of the last and flanged outwardly therefrom are operated upon either singly or together first by being clamped at their marginal portions against a clamp plate 34 at substantially its level, as illustrated in Fig. 1, by wipers 36 which overlap the edge of the clamp plate 34 for reasons which will appear hereinafter. Then the wipers 36 and clamp plate 34 are moved heightwise of the last toward its bottom to pull the upper part or parts into conformity to the top, side and end surfaces of the last, the upper parts being allowed to slip out from between the clamp plate 34 and the wipers 36, the latter toward which the last is urged by the operator being shaped and arranged to hold the upper parts firmly against the side and end surfaces of the last and to impart a down wipe to the upper directed toward the edge of the last bottom. Finally the heightwise movement of the clamp plate 34 and wipers 36 is limited in such a position that the bottom surface of the last (or the bottom of an innersole covering the last bottom) and that of the outwardly flanged marginal portions of the upper parts are substantially in alinement as a result of the upper parts being pressed against the surface 28 of the support 26 by the portions of the wipers which overlap the clamp plate 34, as illustrated in Fig. 8. The mechanism for carrying out this operation will now be described in detail.

The clamp plate 34 is removably fastened by a screw 38 to a carriage 40, the latter being rotatably connected by a stud 42 (Fig. 3) to an arm 44 so as to permit heightwise movement of the clamp plate 34 from its position in Fig. 1 to that in Fig. 8 in which its upper surface and the surface 28 of the support 26 are substantially in the same plane.

The contiguous edges of the clamp plate 34 and support 26 are substantially complementary, thereby to provide an uninterrupted support against which the outwardly flanged portions of the upper parts may be pressed. The above-mentioned pivotal movement of the carriage 40 about the stud 42 is controlled and limited by a roll follower 46 carried by a stud 48 extending from one side of the frame 14, the roll 46 being received within a guideway having an arcuate section 50 and a rectilinear section 52 extending heightwise and longitudinally of the form respectively. The center of curvature of the arcuate guideway 50 is at the axis of the stud 42 and consequently the carriage 40 has no movement longitudinally of the shoe notwithstanding such swinging move-

ment of the carriage 40 as is required to bring the upper surfaces of the clamp plate 34 and the support 26 into the same plane. The arm 44 is pivotally supported on a stud 54 fixed in the uppermost part of the frame 14. The stud 54 also supports a combined stop and heating member 56 which is bored at 58 to receive an electric resistance heating unit (not shown) and is provided with a relatively broad heat-transmitting surface 60 adapted not only to transfer heat to the carriage 40 and clamp plate 34 but also to limit upward swinging movement of the carriage 40 by engagement with a portion of it adjacent to the clamp plate 34. Provision is made for adjusting the position of the member 56 to insure intimate contact between the surface 60 and the carriage 40 by forming arcuate slots 62, 64 in the member 56 concentric with the axis of the stud 42 and adapted to receive the stud 54 and a clamp bolt 65, respectively. The carriage 40 is yieldingly urged toward its uppermost position, in engagement with the member 56, by a spring 66 one end of which abuts the carriage 40 and the other a shoulder on a rod 67 arranged to slide freely in a perforation in the carriage 40 and pivotally connected to the lower end of the arm 44 by a stud 68.

The wipers 36 disposed normally in planes at an angle to each other are removably secured by hand screws 69 to holders 70 which are mounted to swing on rods 72 fixed in yokes 74, (Figs. 2 and 3) the yokes being mounted to swing laterally of the carriage 40 on a nearly vertical rod 76 fixed in the carriage by means of a set screw 78 (Fig. 1). The rods 72 on which the wiper holders 70 swing are so situated that the corners of the wipers adjacent to the extreme toe end of the last are in juxtaposition and directly over the axis of the rod 76 about which they are laterally adjustable. Accordingly, in spite of lateral adjustment of the wipers 36, they always present a substantially continuous edge to the shoe upper at the toe end of the last. The wiper holders 70 have arms 80 extending toward each other, to the inner ends of which are connected rods 82 extending obliquely with respect to both sections of the guideway 50—52, the rods 82 at their lower ends being connected to the opposite ends of an equalizer bar 84. The bar 84 is pivoted on a stud 86 which is adapted to be clamped in any position of heightwise adjustment on a treadle rod 88 by a set screw 90. The bar 84 may also be swung about the stud 86 to equalize the heightwise relation between the wipers 36 and the clamp plate 34 and may be held in any adjusted position by a clamp bolt 92 adjustably fixed to the treadle rod 88 and received in an arcuate slot 94 formed in an extension 96 of the bar 84. The treadle rod 88 is guided at its upper end by a bearing in the arm 18 and may be actuated by any suitable treadle mechanism connected to its lower end.

Usually it is preferable to heat the wipers 36 as well as the clamp plate 34 for the purpose of softening the box toe material and setting the upper parts as they are shaped about the last and when their margins are flanged outwardly against the support 26 and clamp plate 34. To this end a heat-conducting plate 98 is fastened to the upper side of the heating unit 56 in such a position as to have intimate contact with flattened heat-receiving surfaces 100 on the wiper holders 70 through which heat is transmitted to the wipers 36. The wipers 36 and their holders 70 are normally urged away from the clamp plate 34 by a tension spring 101 which connects

the bottom of the frame 14 with the treadle rod 88 at a point below the clamp 92 and which is sufficiently strong to overcome the weight of the treadle-operated mechanism for causing the wipers 36 to grip the shoe parts against the 5 clamping plate 34. Moreover, the strength of the spring 66 is sufficient to prevent the carriage 40 from being swung downwardly in response to the pressure of the wipers 36 until the desired gripping pressure on the upper parts has been 10 set up between the wipers 36 and the clamp plate 34. It will be observed that the plate 98 normally limits the upward movement of the wiper holders 70; but if, for any reason, it is not desired to heat the wipers 36 and the plate 98 is removed 15 from the machine, upward movement of the wipers 36 is then limited by screws 102 against the heads of which the equalizer bar 84 may strike.

The shoe-upper-engaging edges of the wipers 20 36 are shaped substantially in conformity to the edge of the last bottom at its toe so as to be capable of holding all portions of the upper parts along lines parallel to the last bottom and extending continuously about the toe of the shoe 25 26 closely against the last when the latter is urged by the operator toward the wipers 36. However, a given pair of wipers 36 may be utilized to operate on shoes of various sizes within a certain range by slightly varying their angular relation, 30 which is determined by the position of the yokes 74. To this end, the yokes 74 may be swung simultaneously through equal angles by an adjusting means comprising links 104, connecting the yokes, and a nut 106 through which is 35 threaded a screw on a slide 108 which is mounted freely to turn and move axially within spaced bearings 110 in the carriage 40. Thus, when the slide 108 is turned, a hand wheel 112 being provided for this purpose, the nut 106 is moved longitudinally of the carriage 40 and causes the yokes 40 74 and the wipers 36 to be swung toward and away from each other. The slide 108 is prevented from moving axially, so long as the carriage 40 merely swings about the axis of the 45 stud 42, by a forked member 114, the forked portion of which is received between shoulders 116 at the sides of a recess in the slide 108 (Fig. 3). The member 114 is carried by the upper arm of a bell crank 117 (Fig. 1) pivoted at the 50 lower end of the arm 44, the lower arm 118 of this bell crank being connected to the frame 14 by a link 120 and a pin 121 which may be inserted in any of several holes 122 in the frame 14, as will be described later. It is now apparent 55 that, as long as the carriage 40 is moved so that the roll 46 is within the arcuate slot 50, no movement of the arm 44, bell crank 117—118 or link 120 occurs, and that the axial position of the slide 108 with respect to the carriage 40 is fixed. 60

It will now be understood that in flanging upper parts outwardly from the bottom of the form or last L, the shoe part or parts which are thus to be operated upon are placed over the clamp plate 34, the bottom of the last being held 65 against the surface 28 of the support 26 and the toe end of the last engaging a stop 124. The end of the stop 124 overlies the support 26 to a slight extent to insure the desired extension of the support beyond the toe end of the last, as 70 illustrated in Fig. 8. To avoid interference between the support 26 and the stop 124 as the latter moves downwardly with the carriage 40 the stop is pivotally mounted on a pin 126 fixed to the carriage and is yieldingly held in its oper- 75

ative position by a torsion spring 128. The treadle (not shown) is then operated to swing the wipers 36 into substantially the same plane to grip the upper parts against the clamp plate 34, 5 it being understood that the angular relation of the wipers 36, considered laterally of the last, has already been so adjusted by operating the hand wheel 112 as to make their edges, when in the same plane conform to the shape of the last. 10 Further depression of the treadle rod 88 after the upper parts have been gripped against the clamp plate 34 causes the wipers 36 to hold the upper against the last along a line extending continuously from one side to the other about the 15 toe end and the upper to be pulled heightwise of the last by a down wipe directed toward the last bottom. As the clamp plate 34 approaches the position in which its upper surface and the surface 28 of the support 26 are continuous with 20 each other, the outwardly flanged portions of the upper slip between the wipers 36 and the clamp plate 34 although still being gripped therebetween; and such portions of the outwardly flanged upper which are not engaged by the clamp plate 34 are pressed firmly into engagement 25 with the support 26.

Although the operation of the illustrated machine has been described above with reference to its use in operating upon a lining and box toe at once, it is to be understood that the machine is also adapted to operate upon any individual shoe upper part singly, if it is desired to do so. For example, the machine may have utility in connection with the operation of pre-forming box toes about a last or form prior to their being assembled in a shoe.

The operation of the illustrated machine, in being used to flange the marginal portions of the upper parts inwardly of the last bottom will now be explained. The last is now to be supported with the margin of its bottom unobstructed, the support 26 being swung downwardly, as illustrated in Fig. 2, to allow the last to be supported at points spaced inwardly from the 45 edge of the last bottom by only the horn tip 22 and the studs 24, as illustrated in Figs. 5, 6 and 7.

The marginal portions of the upper part or parts to be flanged inwardly are gripped between the wipers 36 and the clamp plate 34, as 50 illustrated in Fig. 5, when the treadle is depressed and at first are flanged outwardly as they slip between the wipers and clamp plate during their movement toward the bottom of the last. This movement of the wipers 36 and 55 clamp 34, which as explained above is one of rotation about the axis of the stud 42, continues until it is limited by engagement of the roll 46 with the upper side of the rectilinear slot 52 in the carriage 40. The horn 16 will have been adjusted vertically in the arm 18 with reference to this lowest position of the carriage 40 so that the lowermost surface of an insole which may be affixed to the last, is slightly above the upper 60 surface of the wipers 36 so as to permit them to wipe the marginal portions of the upper parts inwardly across the insole which will have been coated with an adhesive to hold the upper parts which are wiped thereagainst. It is to be noted with reference to Fig. 6 that the edges of the 65 wipers 36 overlie the edge of the clamp plate 34 to such an extent that as the upper surfaces of the wipers 36 become continuous with the last bottom the flanged portion of the upper is withdrawn from contact with the clamp plate 70 34 and hence is free, although being held against

the edge of the last bottom by the wipers 36, to be bent abruptly about the edge of the last bottom and to be wiped under it, as will now be described. The wiping of the upper parts under the last bottom is effected by an action 5 of the wipers 36 resulting from moving them longitudinally of the last from the toe toward its heel end and simultaneously swinging them toward each other laterally of the last. The first-mentioned movement of the wipers is caused 10 by the carriage 40 moving toward the left (Fig. 1), swinging at its end supported by the rod 42 about the stud 54 and rolling at its forward end against the roll 46 which bears against the upper side of the slot 52. This movement of the 15 carriage 40 is derived from the treadle pressure exerted through the rods 82 and is resisted by the compression spring 66 which returns the carriage to its uppermost position (Fig. 1) when the treadle pressure is released. The swinging 20 of the wipers 36 toward each other, which is necessary to cause them to wipe the upper at the sides of the last under its bottom, is obtained by moving the slide 108 relatively to the carriage 40 lengthwise thereof, and such relative movement is effected by the bell crank 117, 118 and link 120 whenever the arm 44 is swung about the stud 54, as when the roll 46 is caused to travel in the slot 52. Thus swinging movement of the arm 44 toward the left (Fig. 1) 30 causes the upper arm 117 of the bell crank, the lower arm 118 of which is under control of the link 120, to be swung in a counterclockwise direction, thereby moving the slide 108 with respect to the carriage 40 toward the wipers and 35 causing them to be swung toward each other. Depending upon the extent to which it is desired to wipe the upper under the bottom of the last as illustrated in Fig. 7, the relative movement between the slide 108 and the carriage 40 may be 40 varied for a given amount of movement of the carriage longitudinally of the last by changing the position of the pin 121 in the holes 122.

Provision is made in the illustrated machine for limiting the above described wiping action 45 of the wipers 36 and the longitudinal movement of the carriage 40 to any desired extent by a stop 130 which is rotatably mounted on a stud 132 fixed in the frame 14. The head of a screw 134 threaded in the stop 130 is adapted, when 50 the stop 130 is swung substantially into alignment with the bell crank arm 118, to rest against a shoulder 136, as indicated in dotted lines in Fig. 1. It will now be apparent that the stop 55 130, acting through the bell crank arm 118, positively limits further swinging of the arm 44 and movement of the carriage 40 and wipers 36 after the bell crank arm 118 has been moved into engagement with the head of the screw 134. 60

Having thus described the invention, what I claim as new and desire to secure by Letters Patent of the United States is:

1. In a machine for shaping a shoe upper part about the end of a form, a support having a surface adapted to be engaged by the form bottom and to extend outwardly therefrom to an edge substantially parallel to the edge of the form bottom, a clamp plate having an edge complementary to that of said support, wipers mounted for 65 movement toward and away from the clamp plate, and means for moving said wipers successively to cause them to flange one part of the marginal portion of the upper against said clamp plate and to flange the part of the marginal portion of the 70 75

- upper not engaged by the clamp plate against said support.
2. In a machine for shaping a shoe upper part about the end of a form, a support having a surface adapted to be engaged by the bottom of the form and extending outwardly therefrom to an edge substantially parallel to the edge of the form bottom, a clamp plate having an edge which is substantially complementary to that of said support, wipers mounted for movement toward said clamp plate into overlapping relation with the edge thereof, and means for moving said wipers toward said clamp plate to flange thereagainst the marginal portions of an upper under said wipers and to cause said clamp plate to be moved bodily with said wipers heightwise of the form whereby the portions of the upper under the wipers not engaged by said clamp plate are flanged against said support.
3. In a machine for shaping a shoe upper part about a form, a support having a surface adapted to be engaged by the form bottom and to extend outwardly therefrom to an edge substantially parallel to the edge of the form bottom, means for flanging the upper part comprising a member the work-engaging surface of which has an edge which is complementary to the edge of said support, said member being mounted for movement into a position such that its work-engaging surface is substantially continuous with the form-engaging surface of said support, and a wiper overlapping the edge of said member and mounted for movement heightwise of the form to flange one section of the marginal portion of the upper against said member and then to move with said member to pull the upper part into conformity to the form and to flange the remainder of the marginal portion of the upper against said support.
4. In a machine for shaping a shoe upper part about the end of a form, a support having a surface adapted to be engaged by the form bottom and to extend outwardly therefrom to an edge substantially parallel to the edge thereof, means for flanging the upper part outwardly of the form comprising a member shaped and arranged to form a continuation of said support, and wipers mounted for movement heightwise of the form and co-operating with both said member and said support to flange the marginal portions of the upper outwardly from the form in the same plane as the form bottom.
5. In a machine for shaping a shoe upper part about the end of a form, a support having a surface adapted to be engaged by the form bottom and to extend outwardly therefrom to an edge substantially parallel to the edge thereof, means for flanging the marginal portions of the upper part outwardly from the form comprising a member the work engaging surface of which has an edge which is complementary to the edge of said support, said member being mounted for movement into a position such that its work engaging surface is substantially continuous with the form engaging surface of said support, and wipers mounted to overlap the edge of said member and mounted for movement heightwise of the form to flange one part of the marginal portion of the upper against said member, and to flange the remainder of the marginal portion of the upper against said support.
6. In a machine for shaping a shoe upper part about the end of a form, a clamp plate mounted for movement heightwise of the form, wipers disposed normally in planes at an angle to each other mounted for movement toward the clamp plate into substantially the same plane to flange the margins of the upper part against said clamp plate outwardly of the form, and means constructed and arranged successively to move said wipers toward the clamp plate and then to cause said clamp plate to move with the wipers heightwise of the form to impart a down wipe to the upper parts about the end of the form.
7. In a machine for shaping a shoe upper part about the end of a form, a clamp plate mounted to swing heightwise of the form, wipers disposed normally in planes at an angle to each other mounted for movement relatively to each other toward said clamp plate to flange the marginal portion of an upper under said wipers outwardly of the form against said clamp plate, and operator-controlled means operable with a continuous movement successively to move said wipers toward said clamp plate and to cause said wipers to move said clamp plate therewith heightwise of the form to impart a down wipe to the upper parts about the end of the form.
8. In a machine for shaping a shoe upper part about the end of a form, a clamp plate, a carriage supporting said clamp plate mounted to swing heightwise of the form, wipers mounted on said carriage for movement relatively to each other toward said clamp plate to flange thereagainst the marginal portions of an upper under said wipers, and operator-controlled means connected to said wipers for successively moving the wipers toward the clamp plate and then swinging the wipers and clamp plate together heightwise of the form to impart a down wipe to the upper parts about the end of the form.
9. In a machine for shaping a shoe upper part about the end of a form, a support for the form, a carriage mounted for movement successively heightwise and longitudinally of the form, wipers disposed normally in planes at an angle to each other and mounted on said carriage for movement into substantially the same plane to hold the shoe upper part against the end of the form, said wipers also being mounted to swing relatively to each other laterally of the form, a slide mounted in said carriage, means actuated by movement of said carriage longitudinally of the form to impart movement to said slide relatively to said carriage, and connections between said slide and wipers for swinging the wipers laterally of the form during movement of said carriage longitudinally of the form.
10. In a machine for shaping a shoe upper part about the end of a form, a support for the form, a carriage mounted for movement heightwise and longitudinally of said form in succession, wipers disposed normally in planes at an angle to each other mounted on said carriage to swing into substantially the same plane to hold the upper part against the toe end of the form and to impart a down wipe to the upper part during said movement of the carriage heightwise of the form, means for operating said wipers laterally of the form comprising a slide mounted on said carriage, and means constructed and arranged to prevent relative movement between said slide and carriage whereby said wipers are swung laterally of the form to wipe the upper part inwardly across the bottom of the form.
11. In a machine for shaping a shoe upper part about the end of a form, a support for the form, a

carriage mounted for movement successively heightwise and longitudinally of the form, wipers mounted on said carriage and adapted to impart a down wipe to the upper part on said form during 5 heightwise movement of the carriage, said wipers being mounted to swing laterally of the form, a slide mounted for rotative and axial movement in said carriage, means connecting said slide and wipers for adjusting the wipers laterally of the 10 form when the slide is rotated, and means actuated by movement of said carriage longitudinally of the form for imparting an axial movement to said slide relatively to the carriage thereby to swing the wipers toward each other to wipe the 15 upper part inwardly across the bottom of the form.

12. In a machine for shaping a shoe upper part about the end of a form, a support for the form, a carriage mounted for movement successively heightwise and longitudinally of the form, wipers 20 disposed normally in planes at an angle to each other mounted on said carriage to swing into substantially the same plane and for adjustment laterally of the form, a slide mounted for rotative and axial movement in said carriage, screw connections 25 between said slide and wipers for adjusting the wipers laterally of the form when said slide is rotated, and means actuated by a movement of said carriage longitudinally of the form for imparting an axial movement to said slide relatively to the carriage thereby to swing the wipers 30 laterally of the form.

13. In a machine for shaping a shoe upper part about the end of a form, a support for the form, a carriage mounted for movement successively heightwise and longitudinally of the form, wipers mounted on said carriage to swing toward and away from each other laterally of said form, means for operating said wipers comprising a member mounted on said carriage for movement relatively thereto, means for moving said member relatively to the carriage mounted and arranged to be actuated by movement of said carriage longitudinally of the form, and a stop associated with said last-mentioned means for limiting the movement of said carriage and said member. 5

14. In a machine for shaping a shoe upper part about the end of a form, a support for the form, a carriage having a guideway comprising connected sections extending heightwise and longitudinally of the form, a follower received in said guideway, wipers mounted on said carriage to swing laterally 10 of the form, treadle-operated means movable with a continuous stroke in a direction oblique to said sections of the guideway to cause said wipers successively to move heightwise of the form to impart a down wipe to an upper part thereon and then 15 lengthwise of the form to wipe the upper part inwardly across the bottom of the form, and means actuated by movement of said carriage longitudinally of the form to swing said wipers laterally of the form. 20
